UNITED STATES PATENT OFFICE.

JOHN EIBERWEISER AND EDWARD KETTLER, OF CINCINNATI, OHIO.

DESIGN FOR A STOVE.

Specification forming part of Design No. 1,524, dated February 11, 1862.

To all whom it may concern:

Be it known that we, JOHN EIBERWEISER and EDWARD KETTLER, of Cincinnati, in the county of Hamilton and State of Ohio, have invented a new and original Design for a Stove; and we do hereby declare that the following is a clear and exact description thereof, reference being had to the accompanying drawings, and letters of reference marked thereon, making part of this specification.

Our stove is intended for burning coal; and our design relates to its general form and particularly to the finish of the main body, which is of polished or highly-finished cast metal.

Figure 1 of the annexed drawings is an elevation. Fig. 2 is a top view.

B is the base, having an octagonal form and resting upon the hearth or floor.

A is the main body of the stove. This part is slightly conical.

C is the cornice or capping, which is surmounted with a ball, as shown.

a is the ash-pan.

b b are apertures for the admission of air to supply combustion, and c is the door through which fuel is introduced.

Having described our invention, what we claim as new and original is the following:

The design of a parlor or office stove, substantially as herein represented and described.

In witness whereof we have hereunto set our names.

JOHN EIBERWEISER.
EDWARD KETTLER.

Witnesses:

CHARLES L. FISHER,
WM. CLOUGH.
